UNITED STATES PATENT OFFICE.

HERBERT H. DREW, OF WATERLOO, WISCONSIN.

ELEVATED CARRIER.

SPECIFICATION forming part of Letters Patent No. 608,656, dated August 9, 1898.

Application filed September 1, 1897. Serial No. 650,254. (No model.)

To all whom it may concern:

Be it known that I, HERBERT H. DREW, a citizen of the United States, and a resident of Waterloo, in the county of Jefferson and State 5 of Wisconsin, have invented certain new and useful Improvements in Elevated Carriers; and I do hereby declare that the following is a full, clear, and exact description thereof.

My invention contemplates a dump-carrier 10 and elevated track for the same having turns. It therefore consists in certain peculiarities of construction and combination of parts hereinafter set forth, with reference to the accompanying drawings, and subsequently claimed.

Figure 1 represents a side elevation of a 15 partly-broken dump-carrier and a portion of an elevated track for the same; Fig. 2, a partly-sectional end view of the assemblage of parts shown in the preceding figure, and Fig. 3 a perspective view illustrating a turn 20 in the track and a trolley-wheel in travel thereon.

Referring by letter to the drawings, A represents a wire that constitutes the major portion 25 of a track for a traveler, comprising a horizontal bar B, having a longitudinally-grooved upper face, a plate C, made fast to the bar and turned over at its upper end to form a housing having vertical side slots b, 30 horizontal axles D, engaging said slots, and trolley-wheels E, loose on the axles, the grooved peripheries of these trolley-wheels being engaged with the said track. In detachable engagement with the grooved bar B

35 of the traveler is a bail F, herein shown as having its ends in screw-thread union with castings G, these castings being provided at their lower ends with eyes that engage pivot-studs d, projecting from other castings H, 40 made fast to the ends of a box I, the latter constituting a carrier, that is held in position for loading by means of slip-pins J, that engage each pair of the aforesaid castings. However, various means may be employed for 45 holding the box I in position for loading, it being understood that the pivotal connections of said box and its bail are so positioned that the former will automatically dump when the pins J or other holders are retracted.

The apparatus herein described is especially designed for use about stables and

barns as a means for handling feed, manure, or other material, and from the foregoing it will be understood that a change of boxes with respect to the traveler may be readily 55 made whenever desirable.

The track-wire is connected to any convenient supports, and where it has a turn a switch K is employed in the angle. The switch is preferably a rail of J-iron bent to the desired 60 curve, its horizontal portion being notched and shaped to fit upon stretches of the wire. The horizontal portion of the switch is also of less length than the vertical portion of the same and has its ends provided with upturned 65 lips e, upon which said stretches of the wire have bearing. By means of eyes f g and rods h the switch is made fast to the turn in the track-wire, and any suitable means may be employed for the suspension of said switch in 70 order to take its weight from said track-wire. The ends of the vertical portion of the switch come inside the track-wire, on a level therewith, and hence it will be seen that the trolley-wheels of the traveler will readily shift 75 from said track-wire to said switch or from the latter to the former, and provision being had for vertical play of the wheel-axes the traveler will not only run smoothly on an inclined stretch of track-wire, but will also go 80 onto the switch without liability of its rear-most wheel leaving the said wire.

Having thus described my invention, what I claim as new, and desire to secure by Letters Patent, is—

1. An elevated carrier having a track comprising diverging stretches of wire and a curved switch made from a rail of J-iron having its horizontal portion notched and shaped to fit upon the wire stretches, this portion of 90 the rail being of less length than the vertical portion of the same and turned up to form lips upon which said wire stretches have bearing.

2. A suitable track, a traveler comprising 95 a horizontal bar having a longitudinally-grooved upper face, a plate rising from the bar and bent over at its upper end to form a housing provided with vertical side slots, axles engaging the slots and trolley-wheels on 100 the axles having grooved peripheries engaged with the track, a bail that detachably engages

the grooved traveler-bar, a box having pivotal dump connection with the bail, and suitable means for holding the box in position for loading.

- 5 3. A track comprising diverging stretches of wire and a curved switch-rail having connection with the wire stretches within the angle formed by the same, a traveler comprising vertical-play trolley-wheels engaged with
10 the track, a pivotal dump-box hung from the

traveler, and suitable means for holding the box in position for loading.

In testimony that I claim the foregoing I have hereunto set my hand, at Waterloo, in the county of Jefferson and State of Wisconsin, in the presence of two witnesses.

HERBERT H. DREW.
